[57] CLAIM

The ornamental design for a flat bed knitting machine,
as shown and described.

DESCRIPTION

FIG. 1 is a front elevational view of a flat bed knitting machine showing my new design;
FIG. 2 is a rear elevational view thereof;
FIG. 3 is a side elevational view of one side thereof;
FIG. 4 is a side elevational view of an opposite side
thereof; and,
FIG. 5 is a perspective view thereof showing the front,
top and said opposite side.

FIG. 1

FIG. 2

FIG. 4

FIG. 3

FIG. 5
